PERCY DELANY, OF PHILADELPHIA, PENNSYLVANIA, ASSIGNOR OF ONE-HALF TO
EDWARD SCHOEPPE, OF PHILADELPHIA, PENNSYLVANIA

SWIMMING POOL

Application filed September 14, 1928. Serial No. 306,079.

The rapidly increasing demand for facilities to provide bathing, swimming and diving aquatic recreation has recently resulted in the construction of numerous pools for the purpose of satisfying such demand. It has been found impractical, however, to provide the maximum enjoyment for an average group of bathers in a single swimming pool since their demands differ greatly depending on their swimming and diving abilities and other factors resulting in considerable interference, sometimes dangerous, between small children, bathers, swimmers and divers. It has been customary to provide a single swimming pool with a sloped or stepped bottom to provide the varying depths demanded by the several classes. This plan has been found wasteful in that there is considerable waste water between the depths adapted for the separate classes and it has been found extremely dangerous to so construct the pool that there is a sharp declivity between the various depths since this results in bathers unexpectedly stepping into water dangerously deep.

A further disadvantage in the use of but a single pool arises from the waste of water and the temporary putting of the pool out of use when the bottom and walls of the pool are cleaned, the withdrawal or removal of all of the water being required which is usually drained away and is no longer available for the pool when it is to be refilled. The cost of water in some locations is a heavy item of expense and the loss of revenue while the pool is not capable of use is irrecoverable.

My invention is directed to overcoming these and other disadvantages and in doing so I provide a plurality of interconnected pools of varying depths, each being adapted to the requirements of the several classes of patrons. In practice I have constructed a swimming pool unit comprising a wading pool for small children, a bathing pool for bathers or non-swimmers, a pool adapted for swimmers only and a diving pool, each of which is enclosed by four walls, portions of the walls of the main or bathing pool serving also as a wall for the other three pools which I have mentioned. In my improved swim-

ming pool unit I also provide suitable influent and effluent pipes and valves therefor whereby when it is desired to exhaust the water from one of the pools for cleansing purposes the water may be carried to and stored in one or more of the other pools and, after the cleaning operation has been finished, returned to the cleaned pool. By this improvement I save the cost of water and also expedite the cleaning operation whereby the pool which is being cleaned is out of use for a minimum length of time.

Moreover, by providing a plurality of interconnected pools in my swimming pool unit, each being adapted for the use of patrons of the different classes above mentioned, the likelihood of accidental injury to a patron from collision is practically eliminated, particularly injury which might result from being struck by a diver.

Another desirable object derived from my invention resides in the fact that all of the pools except the one being cleaned may be kept in operation meanwhile, thereby avoiding the loss of revenue from the users of the pools which would otherwise result.

The storage capacity for the water which is removed from a pool is obtained by providing the scum gutters which are provided in each wall of each pool, preferably about a foot from the top of the walls, with drain valves which when closed operate to prevent the water from passing into the drain. The capacity of a pool when the drain valves are closed is thereby increased by a volume dependent on the area of the pool and the location of the scum gutters.

I also preferably construct the partitions or walls of the pools of sufficient width to permit convenient arrangement therein of the piping and afford ready access thereto, the deck resting upon the walls providing sufficient area for a walk or promenade around each pool and also as a cover for the pipes.

The piping arrangement is such that the entire filter and pumping plant can be used simultaneously on all of the pools or concentrated on a plurality of them or on but one. Furthermore, the drain lines or pipes from the bottoms of the pools all lead separately to

the sump which permits the drainage of one or more of the pools without interfering with the remaining pools.

The method and means whereby the objects 5 of my invention may be attained is described hereinafter more particularly, reference being had to the accompanying drawings in which reference characters indicate like parts.

10 Fig. 1 is a plan view of one embodiment of my swimming pool unit and the sump and filter plant; Fig. 2 is a sectional view on the line 2—2 in Fig. 1; Fig. 3 is an enlarged sectional view on the line 3—3 in Fig. 1; Fig. 15 4 is a diagrammatic representation of the arrangement of the piping system and other apparatus for use in operation of the pools.

When my swimming pool unit is to be installed outdoors it is desirable that suitable terrain be chosen so that the pool bottoms and walls may be supported thereby.

In a preferred form of my invention, as illustrated in the drawings, the swimming pool unit comprises a bathing or main pool

25 A preferably constructed with a gently sloping bottom of such depth as to provide recreation for non-swimmers but of insufficient depth to be dangerous for such persons and may therefore be so constructed as to provide 30 a water depth of about three feet at the edges of the pool, the depth increasing to about four and one-half feet at the deepest part; swimming pool B is preferably constructed so as to provide a water depth too great for

35 non-swimmers and of sufficient length to provide a reasonable distance for swimming; diving pool C is constructed so as to provide sufficient depth to permit safe diving from diving boards; and wading pool

40 D is relatively shallow, being of such depth that children may safely bathe therein. A pit or sump E is provided for the storage of water drained from the pools, to which is connected a pump F and a filter or other 45 purification plant G.

The partitions 1 between adjacent pools are preferably formed of concrete and are of the bulkhead type, are constructed so as to provide space therein for the water pipes, 50 and comprise two separate walls 2 and 3 spaced from each other, thereby providing an opening extending longitudinally between them for enclosing the piping arrangement. A deck 4 rests upon the tops of the walls 2 55 and 3 and serves to enclose the pipes and also as a walk for the patrons. The outer walls 5, which also are preferably of concrete, of the several pools are provided with decks 6 which may be used as promenades 60 and beneath which pipes may be placed.

The bottom 7 of pool A preferably slopes downwardly from the edges of the pool, the greatest depth of the pool being near the center thereof above the drain 8. The bottom 65 9 of pool B preferably slopes downward-

ly from one end toward the other end, the greatest depth being over the drain 10. The bottom 11 of pool C preferably slopes downwardly from one side toward the other side, affording the greatest water depth above 70 the drain 12, and the bottom 13 of pool D slopes downwardly from its edges towards the center of the pool, providing the greatest water depth over the drain 13'.

Extending throughout all the walls of the 75 pools are surface drains or scum gutters 14 opening into the pools and preferably located about a foot below the tops of the walls. At intervals in the bottoms of the scum gutters are provided drains 15 which conduct the water and floatage flowing into the scum gutters through suitable piping 16 into the pit or sump E. It will be understood that while the drains 15 of the scum gutters are open the water within the several pools will be maintained at the scum gutter level, the 80 excess of water which would otherwise be provided by the continuous pumping of fresh water into the pools flowing into the scum gutters and passing therefrom to the pit or sump E through suitable ducts and pipes. Valves 17 are interposed in the pipes 16 and when these are closed the discharge of water from the pools through the scum gutters is stopped. I utilize these means for preventing discharge of water from the pools through the scum gutters so as to provide desired storage capacity for water as will appear hereinafter.

In diving pool C I preferably provide 100 diving boards 18 arranged at different heights to suit the varying degrees of skill and competency of individual divers and on the opposite end of the pool I preferably provide ladders 19 so disposed opposite to the diving boards that the divers may 105 reach the ladder nearest them without crossing the paths of other divers, thus resulting in the minimizing of the danger of divers colliding with or falling upon each other.

Connected by suitable piping 20 to the sump E is the pumping plant F whereby water from the sump E may be pumped into the purification apparatus G and thence through suitable piping 21 back to the pools, 110 preferably through the several ports 22 disposed within the walls of the pools and through the central fountain 23 in pool A. Valves 24 are provided in influent piping 21 whereby the flow of water into any pool may 115 be stopped as desired.

Pipes 25 lead from the drains in the bottom of each pool whereby, when desired, the water in each pool may be conducted to the sump E, pipes 25 being provided with valves 120 26 controlling the flow of water therethrough.

Between each of the smaller pools B, C and D and the large pool A and between pools B and C are connecting balance pipes 27 pro-

vided with valves 28, which when open will permit the water to flow between the adjacent connected pools when there is a difference in the water level. In the ordinary operation of the pools these valves 28 are kept 5 opened and the pump operates to maintain a constant circulation of water through all the pools and to maintain the body of water in each pool level with the edge of the scum gutter, water for the initial filling of the 10 pools being admitted to the system from the outside main 29 leading from a source of supply not shown. A drain 30 is provided to permit draining of the entire system into a sewer. It will be understood that during the 15 ordinary operation of the pools after the initial filling the main 29 and the drain 30 are closed by suitable valves.

When it is desired to empty one of the 20 pools for cleaning or for any other reason the operation is as follows: The valves 24 through which the water from the filter flows into the pool desired to be emptied are first closed, preventing the admittance of water 25 into that pool. The valves 26 in the pipes leading from the drains in all the other pools 30 are then closed and the valve 26 in the pipe 25 leading from the drain of the pool being emptied is then opened, thus permitting the water from that pool to flow into the sump E as that pool is the only source of water now 35 flowing into the sump. From the sump E the water is pumped by the pump F through the filter G and into the remaining pools, escape 40 of the water therefrom through the scum gutters being prevented by closing the valves 17 in the pipes 16. These pools are therefore 45 filled to a higher level than normal, thereby affording capacity for the storage of the water from the emptied pool, the water then occupying the space, ordinarily unoccupied, 50 between the level of the edge of the scum gutters and the level of the top of the walls of the pool. It will be understood by those 55 familiar with the art that this space between the edge of the scum gutter and the top of the wall is ordinarily about a foot in height 60 above the normal water level and although I do not confine myself to any particular dimensions it will be apparent that a large volume of water may be stored in this space and the water from the pool being emptied thus saved. When it is desired to refill the 65 emptied pool after cleaning it is necessary only to open the valves 28 in the balance pipes 27 thereby permitting the water in all the pools to adjust itself to the same level after which the valves 28 may be closed and the operation 70 of the pool continued in the ordinary way.

60 While I have herein described and in the accompanying drawings illustrated a preferred form of my invention with considerable particularity, I do not thereby desire or intend to limit myself specifically thereto 75 as it will be understood that changes of con-

struction and arrangement may be made if desired without departing from the spirit and scope of the invention as defined in the appended claims.

Having thus described my invention, I claim and desire to protect by Letters Patent of the United States:

1. A swimming pool unit comprising a plurality of interconnected pools, means for transferring water from one pool to another 75 pool, and means for retransferring the water.

2. In a swimming pool unit comprising a plurality of pools, means to exhaust the water from one of the pools and to convey said water to another pool, and means to equalize the 80 water level in all the pools by gravity.

3. In a swimming pool unit comprising a plurality of pools, a pump, a filter plant, pipes for conducting the water from the several pools to the filter plant, means for selectively exhausting water from one pool, and means for conveying said water into one or 85 more of the remaining pools.

4. In a swimming pool unit comprising a plurality of pools, a pump, a filter plant, pipes 90 for conducting the water from the several pools to the filter plant, means for selectively exhausting water from one pool, means for conveying said water into one or more of the remaining pools, and means to permit the 95 flow of water into the exhausted pool from the remaining pools.

5. In a swimming pool unit, a plurality of bathing pools, scum gutters disposed about the walls of said pools at the water level, 100 drains for said scum gutters, a sump, pipes leading from said drains to said sump and adapted to convey water to said sump, control valves in said pipes, a filtering apparatus, a pump adapted to force water from the sump through said filtering apparatus, 105 pipes adapted to convey water from said filtering apparatus to said pools and to distribute a portion thereof to each, control valves in 110 said last mentioned pipes whereby the delivery of water to any of said pools may be made selectively, a drain in the bottom of each of said pools, pipes adapted to conduct water from said drains to said sump, control valves disposed in said last mentioned pipes adapted to selectively control the flow of water from 115 said drains to said sump, pipes disposed between and connecting adjacent pools adapted to convey water from each to the other adjacent pools and control valves in said last mentioned pipes.

6. A swimming pool unit comprising a plurality of bathing pools, a piping system adapted to maintain continuous circulation of water in the pools and comprising means to withdraw water from one pool while maintaining the water in the remaining pools, 125 means to deliver to said remaining pools the water withdrawn from said pool and means to retain said water in said pools.

- 7: In a swimming pool unit comprising a plurality of adjacent bathing pools, the method of withdrawing the water from one of said pools, of storing said water in one or 5 more of the remaining pools and of refilling the pool from which the water has been withdrawn by conducting water thereinto from said remaining pools.

In witness whereof I have hereunto set my
10 hand this 13th day of September, 1928.

PERCY DELANY.
